Attn: G.S.

REEL 10 is rotatably mounted between the arms 14 and 16 of a support member 18. The support member 18 may take any suitable form but a bifurcated member adapted to have the reel 10 rotatably mounted between the two arms thereof has been found to be the most preferable.

Other objects and advantages of a dispenser embodying this invention are that the free end of the wire is frictionally braked at all times, which prevents the wire from uncoiling in an uncontrolled fashion; that suitable means is provided for adjusting the frictional drag on the reel to provide proper tension with relation to the supporting member so that the reel can be readily revolved when it is desired to dispense the wire, but nevertheless there is no danger of the wire uncoiling in an uncontrolled manner; and that a dispenser is provided which is simple both in construction and operation, and which can be manufactured at relatively low cost.

In addition, the design of the dispenser is such

that the supporting member for the reel which also includes the braking and straightening mechanism may be readily removed from the supporting reel which carries the supply of wire, when that supply is exhausted, and a new reel carrying a new supply of wire may be easily mounted in dispensing position in the supporting member. This characteristic permits the purchaser of such a dispenser to replace the supply

coil of wire without the necessity of having to repurchase a complete dispenser, including the support member.

Further objects and advantages of this invention will become evident as the description proceeds and from an examination of the accompanying drawing which illustrates one embodiment of the invention and in which similar numerals refer to similar parts throughout the several views.

20 In the drawings:

Figure 1 is a view in side elevation of one form of dispenser embodying this invention, the dispenser being shown in dispensing position in the hands of a user;

25 Figure 2 is an enlarged view in elevation, and partly in vertical cross-section, of the dispenser shown in Figure 1; and

Figure 3 is an end view in elevation and particularly in cross-section of the dispenser shown in Figure 2.

30 Referring now to these figures, the reel 10 which is adapted to carry a supply of highly resilient wire 12 is rotatably mounted between the arms 14 and 16 of a suitable support member, such as that indicated generally by the numeral 18. This support member may take any suitable form but a bifurcated member adapted to have the reel 10 rotatably mounted between the two arms thereof has been found to be the most preferable.

35 The reel 10 may be formed of two disks 20 and 22, having the shoulders 24 and 26 and the flanges 28 and 30 respectively formed adjacent the peripheral edges thereof, as best shown in Figure 3. The disks 20 and 22 may be secured in abutting and aligned relation by the insertion of the lugs 32 stuck from the disk 20 through the slots 34 formed in the disk 22, and the subsequent crimping of the lugs 32 against the disk 22, as best shown in Figure 3. This disposition of the two disks 20 and 22 causes them to form a reel having a wire supporting surface formed by the shoulders 24 and 26 which surface is disposed between the two upstanding flanges 28 and 30.

50 A supply of the wire 12 may be wound on the reel

WIRE DISPENSER

Robert E. Johnson, Chicago, Ill.

Application January 13, 1949, Serial No. 70,614

6 Claims. (Cl. 242—77)

1

This invention relates to a dispenser for highly resilient wire and more particularly to a dispenser which overcomes the difficulties normally incident to the handling of a coiled wire of this character, such as music wire.

When attempting to dispense highly resilient wire from unsupported coils, difficulty is often encountered in successfully removing the desired amount of wire without producing a snarling of the coil. In addition, if any substantial length of wire is removed from the coil the portion so removed will also have a tendency to retain a coiled form, which characteristic also makes it difficult to handle.

It is therefore an object of this invention to provide a dispenser for highly resilient wire which permits the removal of any desired quantity of such wire from a compact coil without the danger of snarling either the supply coil or the dispensed portion of the wire. It is a further object to provide such a dispenser which is so designed that the tendency for the wire to remain in a coiled form is eliminated as the wire is removed from the supply coil, and the wire therefore emerges in a substantially straight form which greatly increases the ease of handling the portion of wire dispensed.

Another object of this invention is to provide a dispenser which permits a more economical use of the wire, since it allows closer measurements to be made before cutting, and also prevents tarnishing of the unused portion of the wire from finger contact. This latter advantage grows out of the fact that the dispenser permits the removal of the required amount of wire without requiring the hands of the individual so moving the wire to come into contact with the supply coil itself. Undesirable corrosion of the supply coil which otherwise often occurs is therefore prevented.

Other objects and advantages of a dispenser embodying this invention are that the free end of the wire is frictionally braked at all times, which prevents the wire from uncoiling in an uncontrolled fashion; that suitable means is provided for adjusting the frictional drag on the reel to provide proper tension with relation to the supporting member so that the reel can be readily revolved when it is desired to dispense the wire, but nevertheless there is no danger of the wire uncoiling in an uncontrolled manner; and that a dispenser is provided which is simple both in construction and operation, and which can be manufactured at relatively low cost.

thus formed, the inner end 36 of the wire being threaded through a suitable opening in the supporting surface formed between shoulders 24 and 26.

Any suitable means may be utilized to rotatably mount the reel 10 between the arms of the support member 18 as mentioned above. This means may take the form of the bolt 38 and nut 40, which provide for the adjustment of the frictional drag exerted on the reel by the ends 42 and 44 of the two arms 14 and 16 respectively of the support member 18. This support member 18 may be of a substantially U-shaped cross-section, as shown in Figure 3, and the lower extremities 42 and 44 of the two arms 14 and 16 may be inwardly displaced so that they are adapted to bear against the central portion of the reel 10 but the main portions of the arms 14 and 16 will have adequate clearance for the wire carrying portion of the reel to rotate therebetween.

The base 46 of the support member 18 may have a depending lug 48 formed integrally therewith on one side thereof, as shown in Figures 2 and 3. An opening 50 substantially of the same diameter as that of the wire 12 may be formed in the lug 48 so that it is adapted to have the free end 52 of the wire 12 threaded therethrough as it leaves the reel 10. In addition, the base 46 of the support member 18 may have an upstanding arm 54 either formed integrally therewith or secured thereto by some suitable means such as the rivet 56. The arm 54 extends upwardly and outwardly away from the lug 48, substantially in the plane of the reel 10, and has the depending lug 58 formed at its outer end. The lug 58 also has an opening 60 formed therein which is adapted to have the free end 52 of the wire 12 threaded therethrough. The two lugs 56 and 58 are preferably disposed in planes which are substantially parallel to the axis of rotation of the reel 10 and the openings 50 and 60 therein preferably have their axes disposed perpendicularly thereto.

In addition, the lug 48, the arm 54 and its depending lug 58 are preferably disposed so that the openings 50 and 60 in the lugs 48 and 58, respectively, are disposed on a line intersecting the surface of the reel upon which the wire 12 is wound. This disposition of the openings 50 and 60 is therefore such that when the free end 52 of the wire 12 is threaded therethrough the portion of wire between these holes has a curvature substantially opposite to that of the portion of the wire wound on said reel.

Because of this disposition described above of the openings 50 and 60, the lugs 48 and 58, and the arm 54, the portion of wire threaded through the openings 50 and 60 is automatically given a curvature which is substantially the reverse of that of the remaining portion of wire wound on the reel 10. When the wire 12 is wound on the reel 10, it is necessarily distorted in such a way that it will tend to retain the curvature which it has when disposed on the reel after it is removed therefrom. This reverse curvature which is given the wire as it passes through the openings 50 and 60 is therefore designed to overcome this winding distortion of the wire to such a degree that the wire emerges from the opening 60 in a substantially straight form. In other words, by distorting the wire in substantially the opposite direction that it was distorted when originally wound on the reel 10, the end result is that the wire is substantially straightened. At the same time the edges of the openings 50 and 60 produce considerable friction when the wire 12

is drawn therethrough and therefore a braking action is also produced, as well as the straightening action.

As mentioned above, the bolt 38 and nut 40 may also be adjusted to vary the amount of friction between the support member 18 and the reel 10 so that the reel itself may also be braked to the desired degree, with respect to its rotation in that support member.

10 The dispensing operation from a dispenser of the type illustrated and described is relatively simple. As shown in Figure 1, the operator grasps the support member between the thumb and forefinger of one hand, and at the same time 15 grasps the free end 52 of the wire 12 between the thumb and forefinger of his other hand. If a pull is then exerted on the free end 52 of the wire 12 in a direction away from the support member 18, the wire 12 will be drawn through the openings 50 and 60, and the reel 10 will be revolved in a clockwise direction as viewed in Figure 1 to permit the unwinding of the wire. After the desired amount of wire has been withdrawn from the dispenser, the exact length needed may be 20 measured before cutting since the wire withdrawn is in a substantially straight form. After the wire is cut, the protruding free end of the wire 12 may be drawn back into close association with the arm 54 and the lug 58 by grasping the support member 18 between thumb and forefinger of one hand and rotating the reel 10 with the other hand in a counter-clockwise direction, as viewed in Figure 1.

When the dispenser and its associated supply 35 spool of wire are marketed as a unit, it will probably be desirable to provide a right-angle bend 62 in the free end of the wire 52 as shown in Figure 2, to insure against this end of the wire being inadvertently withdrawn from the operating position shown.

From the above description it will be seen that 40 a dispenser which embodies applicant's invention may be simple both in construction and operation, and yet such a dispenser provides a method 45 of handling highly resilient wire which eliminates many of the difficulties which have previously been present.

The drawing and the above discussion are not 50 intended to represent the only possible form of this invention, in regard to details of construction. Changes in form and in the proportion of parts, as well as the substitution of equivalents 55 are contemplated, as circumstances may suggest or render expedient, without departing from the spirit or scope of this invention as further defined in the following claims.

What is claimed is:

1. A dispenser for highly resilient wire comprising a support member, a reel rotatably mounted thereon, a portion of said support member being disposed adjacent to the peripheral edge depending toward and substantially in the plane of said reel, a second portion of said support member being similarly disposed and in spaced relation to said first named portions, each said portion having a hole therein adapted to have the free end of a length of said wire wound on said reel threaded therethrough, said holes being disposed on a line intersecting the surface of 60 said reel upon which said wire is wound so that the portion of the free end of said wire between said holes has a slight curvature substantially opposite to that of the portion of the wire wound on said reel, the portions of said support member having the holes therein being disposed in

planes substantially parallel to the axis of rotation of said reel.

2. A dispenser for highly resilient wire comprising a substantially U-shaped bracket, a reel mounted for rotation about its axis on said bracket and between the legs thereof, a lug on the base of said bracket depending toward said reel and having a hole therein of substantially the same diameter as said wire, and an arm carried by said bracket having a similarly depending lug at one end thereof, said last named lug having a similar hole therein, said holes being adapted to have the free end of said wire threaded therethrough.

3. A dispenser for highly resilient wire of the character described in claim 2, further characterized in that said lugs lie in intersecting planes substantially parallel to the axis of rotation of said reel.

4. A dispenser for highly resilient wire of the character described in claim 3, further characterized in that said lugs and said holes therein are so disposed that when the free end of a length of wire wound on said reel is threaded through said holes, the portion of wire between said holes has a curvature substantially opposite to that of the portion of the wire wound on said reel.

5. A dispenser for highly resilient wire comprising a supporting bracket, a reel mounted for rotation about its axis on said bracket, one end of said bracket having a form such that it lies adjacent to the peripheral edge and substantially in the plane of said reel, a portion of said end of said bracket depending toward said reel and having a hole therein of substantially the same diameter as said wire, a second portion of said end of said bracket in spaced relation to said first named portion depending toward said reel and having a similar hole therein, said holes being adapted to have the free end of said wire threaded therethrough, said depending portions and said holes therein being so aligned that when the free end of said wire is so threaded, the portion of wire between said holes has a curvature substan-

tially opposite to that of the portion of wire wound on said reel, so that said holes have a binding and straightening action on said wire as it is dispensed.

5 6. A dispenser for highly resilient wire comprising a supporting bracket, a reel mounted for rotation about its axis on said bracket, one end of said bracket having a form such that it lies adjacent to the peripheral edge and substantially in the plane of said reel, a portion of said end of said bracket being disposed in a plane substantially parallel to the axis of rotation of said reel and having a hole therein of substantially the same diameter as said wire, a second portion of said end of said bracket being disposed in spaced relation to said first named portion in a plane substantially parallel to the axis of rotation of said reel and having a similar hole therein, said holes being adapted to have the free end of said wire threaded therethrough, said portions of said end and said holes therein being so aligned that when the free end of said wire is so threaded, the portion of wire between said holes has a curvature substantially opposite to that of the portion of wire wound on said reel, so that said holes have a binding and straightening action on said wire as it is dispensed.
